Albert J. Fiske
ATTORNEY

UNITED STATES PATENT OFFICE.

FRANK H. NEWTON, OF LOS ANGELES, CALIFORNIA.

RESERVOIR COMB.

Application filed March 20, 1928. Serial No. 263,109.

This invention relates to improvements in a reservoir comb, and has for one of its principal objects the provision of means for readily heating and dispensing a liquid contained within the body of the comb.

One of the important objects of the invention is to provide a hollow bodied comb, for containing hair tonic, hair dressing or the like, each tooth of the comb having a duct leading from the body to the outer point of the tooth, for the convenient dispensing of the tonic or fluid contained within the reservoir.

Another important object of this invention is the provision of means for heating the material contained in the reservoir. It may be desirable in some cases to use a tonic or hair dressing which is of high viscosity and which ordinarily could not be dispensed through the ducts of the comb teeth, hence the heating element can be used for melting the substance and converting it into a liquid state, thereby providing a ready means for applying such material to the hair or scalp.

Other and further important objects of the invention will be apparent from the disclosures in the accompanying drawings and following specification.

The invention, in a preferred form, is illustrated in the drawings and hereinafter more fully described.

In the drawings:

Figure 1 is a side elevation, partially in section, illustrating particularly the comb teeth ducts and the internally positioned heating element.

Figure 2 is an entire sectional view, taken on the line 2-2 of Figure 1.

Figure 3 is a detail top plan view of the electrical switch and heating element mounting.

As shown in the drawings:

The reference numeral 10 indicates generally a handle, provided with a longitudinal bore 12 through which a duplex electrical conductor 14 passes. The inner end of the handle terminates in an externally threaded neck 16 upon which the internal threads of a switch housing 18 engage.

Mounted in the housing 18 and interposed in one of the leads of the conductor 14 is a toggle switch 20 adapted to control the current supply to a high resistance heating element 22 wound upon a preferably cylindrical

mounting 24 composed of insulating material. The mounting 24 is preferably integral with and forms an extension of the housing 18.

Integrally attached to one end of the housing 18 is an externally threaded projecting collar 26 and mounted upon and adapted to engage with the threads of the same, is a cylindrical body or reservoir 28. The outer end of the reservoir 28 is provided with a screw-cap 30 adapted to facilitate the ready filling of the reservoir.

Integral with the lower and outer portion of the cylindrical body is a series of comb-teeth 32, each tooth being provided with a longitudinal duct 34 for the conveying of the material in the reservoir to the outer points of the comb-teeth 32.

Interposed between the reservoir 28 and the upper portion of the comb teeth 32 is a cylindrical compound valve shaft 36, the longitudinal axis of which is positioned parallel to the longitudinal axis of the reservoir. Spaced at intervals corresponding to the spacing of the ducts 34 of the comb-teeth 32 is a series of openings 38 in the shaft 36, positioned transversely to the longitudinal axis thereof. By means of a lever 40 rigidly attached to the shaft 36 and positioned at an end thereof, the same may be rotated thereby placing the openings 38 into and out of alignment with the tooth ducts, thus providing a ready control for the dispensing of the liquid contained within the reservoir.

It is apparent that herein is provided a device which lends itself ideally to the use of dispensing hair tonic, hair dressing and the like. A device which is of simple construction and which may be quickly and conveniently operated, and at the same time does its work efficiently. It is sanitary, and may be readily taken apart for cleaning purposes.

I am aware that many changes may be made and numerous details of construction varied throughout a wide range without departing from the principles of this invention, and I therefore do not purpose limiting the patent granted hereon otherwise than as necessitated by the prior art.

I claim as my invention:

A reservoir comb, including in combination, a handle, housing removably mounted on the handle, a reservoir removably mounted on the housing, a heating element remov-

ably mounted in the reservoir, and a plurality of comb-teeth mounted on the reservoir, each tooth being provided with a duct passing longitudinally therethrough, and means for controlling the flow of liquid from the reservoir through the ducts, said means comprising a cylindrical valve rotatably positioned at the inner ends of the teeth and adjacent the reservoir, the said cylindrical valve being provided with a plurality of transverse openings adapted to be rotated into and out of alignment with the ducts in the comb-teeth. 10

In testimony whereof I affix my signature.

FRANK H. NEWTON.
